MULTIPLE SCALE RULER

Douglas D. Seely, Jr., 20138 Brick Road, South Bend, Ind.

Filed Feb. 28, 1964, Ser. No. 78,821

Term of patent 14 years

(Cl. D52—6)

FIG. 1

FIG. 2

FIG. 3

FIG. 4

FIG. 5

FIG. 6

FIG. 7

FIG. 8

FIGURE 1 is a perspective view of a multiple scale ruler, embodying the present invention;

FIGURE 2 is an end elevational view of the multiple scale ruler shown in FIGURE 1;

FIGURE 3 is a fragmentary horizontal cross sectional view taken on line 3-3 of FIGURE 2;

FIGURE 4 is a top plan view;

FIGURE 5 is a side elevational view;

FIGURE 6 is a bottom plan view;

FIGURE 7 is an enlarged vertical cross sectional view, taken on line 7-7 of FIGURE 4; and

FIGURE 8 is a fragmentary end elevational view illustrating the manner in which the present multiple scale ruler is operated.

I claim:

The ornamental design for a multiple scale ruler, substantially as shown.
